(57) **CLAIM**

The ornamental design for a knife blade grip having protrusions, as shown and described.

DESCRIPTION

FIG. 1 is a perspective view of the knife blade grip having protrusions showing my new design;

FIG. 2 is a right side elevational view, the left side being a mirror image;

FIG. 3 is a front elevational view, the rear being a mirror image;

FIG. 4 is a sectional view taken along line 4—4 in FIG. 3;

FIG. 5 is a top plan view; and,

FIG. 6 is a bottom view.

Broken lines appearing in the drawings are intended to be for illustrative purposes only and form no part of the claimed design.
